PAINT PAIL FOR A PAINT ROLLER

James O. Tidwell, Mountain View, Calif., assignor to E. P. Research, Inc., Los Altos, Calif., a corporation of Delaware

Filed Oct. 23, 1967, Ser. No. 9,099

Term of patent 14 years

(Cl. D64—18)

FIG. 1

FIG. 2

FIG. 3

FIG. 5

FIG. 4

FIG. 1 is a perspective view of a paint pail for a paint roller showing the design of the present invention;

FIG. 2 is a front view of FIG. 1, the rear view being identical;

FIG. 3 is a left side view of FIG. 1, the right side view being a mirror image;

FIG. 4 is a top view of FIG. 1; and

FIG. 5 is a bottom view of FIG. 1.

The dominant features of my design reside in the portions shown in full lines.

I claim:

The ornamental design for a paint pail for a paint roller, as shown and described.
